Primary Examiner — Brett Miller

(57) CLAIM

The ornamental design for a food cutter, as shown and described.

DESCRIPTION

FIG. 1 is a perspective view of a food cutter showing my new design;

FIG. 2 is a Front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the food cutter that form no part of the claimed design.
